COMBUSTION HEATING CONTROL SYSTEM

Fred B. Aubert, Grosse Pointe, Mich.

Original application July 26, 1943, Serial No. 496,099, now Patent No. 2,484,602, dated October 11, 1949. Divided and this application September 10, 1949, Serial No. 115,063

2 Claims. (Cl. 158—28)

1

This invention relates to new and useful improvements in heating apparatus and more particularly to a heating control system therefor.

An object of the invention is to provide a heating apparatus which is particularly adapted for the heating of enclosed spaces in aircraft such for example as the cabin or fuselage.

Another object is to provide a control system for initiating and controlling the burner operating cycle.

Another object is to provide a control by which the supply of fuel is increased upon an increase in the rate of supply of combustion air.

Another object is to provide a control system in which the combustion air pressure controls the starting and stopping of a combustion air blower.

Another object is to provide a control system including means assuring operation of the fuel igniting means prior to the supplying of fuel.

Another object is to provide a control system having a timed control for the heating apparatus.

The invention consists in the improved control system, the cooperative relation of parts and their agroupment in cooperative relation, to be more fully described hereinafter and the novelty of which will be particularly pointed out and distinctly claimed.

In the accompanying drawings, to be taken as a part of this specification, there is clearly and fully illustrated a preferred embodiment of this invention, in which drawing:

The figure shown is a diagrammatic view of an electric control system for heating apparatus.

Referring to the drawings by numerals of reference there is shown a heating control system having an electrically driven timing motor and control therefor. This control system is particularly adapted for use in connection with the heating apparatus shown in my copending application Serial No. 496,099, filed July 26, 1943, now Patent 2,484,602, issued October 11, 1949, of which this application is a division.

In this heating control system there is provided a fuel pump 437 for supplying fuel to a burner which is not shown. The fuel is ignited in the burner by a hot wire resistance igniter 414. The combustion air for the burner is supplied by either a ram air duct (since this apparatus is designed for use in a moving vehicle) or a blower 430. The blower 430 is normally energized when insufficient ram air is being supplied and is stopped by a pressure responsive switch 431 responsive to ram air pressure.

There is a main switch 400, which is a double contact 55

2

throw manual switch having an operating extension or lever 401 operatively connected to its switch arm 402 which is moved to the left, for starting the burner, to engage the switch arm contact with the fixed switch contact 403. The closing of switch 400 completes a circuit from the battery or source of current supply 404 through the lead wire 405 to and through the switch 400 and thence through lead wire 406 to one terminal of the coil 407 of the timing motor controlling relay switch 408. From the other terminal of coil 407, a lead wire 409 extends to the switch arm 410 of a normally closed snap acting cam operated switch 411. From the fixed contact 412 of the snap acting switch 411 a lead wire 413 connects to one terminal of the hot wire igniting means 414 which has its other terminal connected to ground. Operation of switch 400 to close circuit through its contact 403 therefore energizes the igniter 414 and actuates the relay switch 408, provided the igniter circuit is complete and the current supply is sufficient to actuate the relay switch 408. The operation of relay switch 408 pulls the relay switch arm 415 into engagement with the fixed relay contact 416 to close the circuit of the timing motor 417 as follows: From main switch lead wire 406 through lead wire 418, to relay switch arm 415 and its engaged contact 416 to lead wire 419, connected to the closed contact 420 of the normally closed cam operated snap acting switch 421, having its movable switch arm 422 linked for movement in unison with switch arm 410. From the switch arm 422 a lead wire 423 extends to one terminal of the timing motor 417, which has its other terminal connected to ground by a lead wire 424. Energization of timing motor 417 drives its cam member 425 to move the cam clockwise, as indicated by the directional arrow, to move cam 426 out of holding relation to the cam follower thrust member 427 so that the snap acting switches 428 and 429 are moved to closed position. Closure of the blower control switch 428 completes a circuit to the combustion air supplying blower motor 430 through the combustion air pressure responsive or ram switch 431 as follows: From battery lead wire 405 through lead wire 432 to the fixed contact of switch 428, and from its cam operated switch arm 433 via lead wire 434, to the normally closed contacts of ram switch 431 and there-through to the lead wire 435 connected to one terminal of the blower motor 430 having its other terminal connected to ground by lead wire 436. The main switch 400, upon engagement with its

supply pump 437 through the intermediary of relay switch 438. Engagement of switch arm 492 and contact 493, which closes the circuit from the battery 404 to lead wire 406, energizes the relay switch coil 439 having one terminal connected by lead wire 449 to the lead wire 406 and having its other terminal connected to ground by lead wire 441. The cam operated blower switch 428 also controls the energization of the fuel pump motor 437 as it is in series circuit with the low speed fuel pump switch arm 442 by lead wire 443, connected to lead wire 434. Closure of relay switch 438 engages the arm 442 with fixed contact 444, thereby completing the circuit to one terminal of the pump motor 437 via lead wire 445 having therein the low speed resistance 446, the other terminal of the pump motor being connected to ground by lead wire 447. The heating apparatus will now be in operation at low fuel consumption to supply the desired amount of heat in accordance with the combustion air supply provided by the blower. Upon increase in the pressure of the combustion air above the pressure provided by the blower, such as will occur when the vehicle is in rapid movement, the ram switch 431 will break circuit between the blower motor supplying lead wires 434 and 435 and will make circuit from the lead wire to the lead 446 connected to the switch arm 449 of relay switch 438 and movable in unison with the switch arm 442. Since the switch arm 449 is in engagement with fixed relay contact 450, the circuit will be completed from lead wire 448 to the lead wire 451 which connects to the adjustable contact 452 of the resistance 446, thereby shunting out a portion of the resistance 446 to increase the speed of the fuel pump motor 437, in order to provide the necessary quantity of fuel for a proper fuel air mixture with the increased combustion air supply.

The cam member 425 has been rotating at a predetermined rate, preferably a 20 minute cycle, and when the cam 426 has been rotated through 90° it will, at the end of the five minute period, engage the follower thrust member 453 to operate the arms 422 and 449 of the switches 421 and 411 respectively to break the circuit of the timer motor 417 and of the igniter 414. Although the circuit to the timing motor 417 is broken at the relay switch 408 upon opening of switch 411 which deenergizes the relay coil 407, the switch 421 provides a safety control to assure stopping of the timing motor 417 in the event relay switch 408 should fail to open. Upon operation as above described, either at low or high fuel consumption will not be affected by the time of operation of follower member 453 by cam 426. When it is desired to stop operation of the burner, the switch operating member 401 is moved to the position shown in the drawing in which switch arm 402 engages the fixed contact 454 so that the timing motor 417 is reenergized from the battery 404 through the following circuit: From switch contact 454, through lead wire 455 to the closed cam switch 429 and thence via lead wire 456 to the timing motor lead wire 423. Accordingly, if during the interval of reinstated timer motor operation the combustion air pressure has decreased below the predetermined blower pressure at which ram switch 431 remakes circuit between lead wires 434 and 435, the blower motor 438 will again be placed in operation to provide scavenging air for the combustion chamber. Upon the termination of the reinstated operating period of 15 minutes of the timing motor 417, the cam 426

will engage the follower member 427 to open the cam switches 428 and 429 to break the circuits of and stop the blower motor 438 and the timing motor 417 respectively and halting or stopping the cam 426 in its position for the start of another burner heating period when desired.

What is claimed and is desired to be secured by Letters Patent is:

1. A heating apparatus comprising an electrically driven blower for supplying combustion air, a circuit for said blower, an electrically driven pump for supplying fuel for combustion, a circuit for said pump, an electrically driven timing motor, a circuit for said timing motor, a cam operated by said motor, hot wire ignition means for the supplied fuel, a circuit for said ignition means, a relay switch controlling the circuit of said motor and having its coil in series circuit with said ignition means, a pump controlling relay switch having an operating coil, a blower and pump switch operated by said cam upon starting of said motor and controlling the circuits of said pump and said blower, said cam acting upon predetermined running of said motor to open said blower and pump switch, a pair of normally closed switches controlling the circuit of said motor and the circuit of said ignition means and movable to open position by said cam upon predetermined running of said motor, a double-throw switch operable in one position to close the circuits of said relay coil and said operating coil and operable in the other position to close a circuit in shunt with said cam opened motor switch thereby to reinstate operation of said timing motor for predetermined closure of the blower circuit, and a switch opened by said cam to deenergize said timing motor upon opening of said blower switch by said cam.

2. A heating apparatus comprising an electrically driven blower for supplying combustion air, a circuit for said blower, an electrically driven pump for supplying fuel for combustion, low and high speed circuits for said pump, an electrically driven timing motor, a circuit for said timing motor, a cam operated by said motor, hot wire ignition means for the supplied fuel, a circuit for said ignition means, a relay switch controlling the circuit of said motor and having its coil in series circuit with said ignition means, a relay switch having an operating coil and having normally open contacts controlling the lower speed circuit of said pump for low speed operation and having normally open contacts controlling the high speed circuit of said pump for high speed operation, a pressure responsive switch having normally closed contacts controlling the circuit of said blower and having normally open contacts controlling the circuit to said high speed pump open contacts, said responsive switch acting at predetermined increased combustion air pressure to open its normally closed contacts and to close its normally open contacts, a blower and pump switch operated by said cam upon starting of said motor and controlling the circuits of said pump and said blower, said cam acting upon predetermined running of said motor to open said blower and pump switch, a pair of normally closed switches controlling the circuit of said motor and the circuit of said ignition means and movable to open position by said cam upon predetermined running of said motor, a double-throw switch operable in one position to close the circuits of said relay coil and said operating coil and operable in the other position to close a circuit in shunt with said cam opened motor switch thereby

to reinstate operation of said timing motor for predetermined closure of the blower circuit, and a switch opened by said cam to deenergize said timing motor upon opening of said blower switch by said cam.
